CLAIM

The ornamental design for a body composition meter, as shown and described.

DESCRIPTION

FIG. 1 is a front, right side, bottom perspective view of a body composition meter showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof showing a state in which the operation display portion is detached from a body portion of this article; and,

FIG. 9 is a reference front elevational view thereof showing a state in which this article is electrified.

The portions in broken lines are shown for illustrative purposes only and form no part of the claimed design.
